(57) **CLAIM**

The ornamental design for a paint brush, as shown and described.

DESCRIPTION

FIG. 1 is a top, front, left perspective view of a paint brush showing our new design;

FIG. 2 is a front-side view thereof;

FIG. 3 is a back-side view thereof;

FIG. 4 is a left-side view thereof;

FIG. 5 is a right-side view thereof;

FIG. 6 is a top-plan view thereof; and,

FIG. 7 is a bottom-plan view thereof.

The broken line showing in FIGS. 1-7 is for the purpose of illustrating portions of the paint brush and forms no part of the claimed design.

1 Claim, 4 Drawing Sheets
